UNITED STATES PATENT OFFICE.

BENJAMIN PORTER AND EDSON D. BARNUM, OF CANASERAGA, NEW YORK.

LIFTING-JACK.

SPECIFICATION forming part of Letters Patent No. 230,569, dated July 27, 1880.

Application filed June 23, 1880. (No model.)

To all whom it may concern:

Be it known that we, BENJAMIN PORTER and EDSON D. BARNUM, both citizens of Canaseraga, Allegany county, and State of New York, have invented a new and useful Improvement in Folding Jacks for Buggies, of which the following is a clear, full, and exact description, reference being had to the accompanying drawings, making a part of this specification, in which—

Figure 1 represents the jack folded for storing. Fig. 2 represents the jack unfolded and in position to be used. Fig. 3 represents the jack in position when sustaining the weight of the buggy.

Our invention relates to that class of lifting-jacks used in connection with buggies and other light-draft carriages; and it consists in constructing the upper section of the folding jack to unfold and pass beyond the dead-point, and the long arm of the lever to do the same, whereby the lever is automatically held in position while sustaining the rigid weight.

To enable others skilled in the art to make and use our invention, we will proceed to describe the exact manner in which we have carried it out.

In the drawings, A represents the base-support, and B the folding section, of a jack. These two parts are pivoted together at a , as shown in Fig. 2, and provided with the shoulders b , so constructed as to allow the folding

section to pass slightly beyond a vertical position.

On the upper end of the folding section is pivoted, at a' , the lever C, within the jaws E, which project sufficiently far from the face of the folding section as to allow of the long arm of the lever to be brought on a parallel line with the folding section, thereby throwing the point of strain beyond and outside of the pivoted points a a' , thus securing an automatic action of the jack in holding the desired weight, as shown in Fig. 3.

This jack is designed to be folded up, as shown in Fig. 1, and be packed in a convenient case, with a wrench and can of lubricant, and be carried beneath the buggy-seat, ready at hand at all times for use.

Having thus described our invention, what we claim as new, and desire to secure by Letters Patent, is—

A folding buggy-jack, constructed as described, and consisting of the base-support, a folding section opening beyond the dead-point, and the lever folding back on a parallel line with the folding section, substantially as and for the purpose set forth.

BENJAMIN PORTER.
EDSON D. BARNUM.
